(57) **CLAIM**

The ornamental design for a combined bottle for eye shower and wall mounting bracket therefor, as shown and described.

DESCRIPTION

FIG. 1 is a top, front, and right side perspective view of a combined bottle for eye shower and wall mounting bracket therefor showing our new design;

FIG. 2 is a front elevational view thereof;

FIG. 3 is a left side elevational view thereof;

FIG. 4 is a bottom plan view thereof;

FIG. 5 is a top plan view thereof;

FIG. 6 is a top, front, and right side perspective view of the wall mounting bracket thereof, the bottle omitted for clarity of illustration;

FIG. 7 is a top, rear, and right side perspective view of the bottle thereof, with the wall mounting bracket omitted for clarity of illustration;

FIG. 8 is a right side elevational view of the bottle thereof;

FIG. 9 is a front elevational view of the bottle thereof;

FIG. 10 is a top plan view of the bottle thereof;

FIG. 11 is an exploded top, rear, and right side perspective view of the bottle thereof; and,

FIG. 12 is a front, and left side perspective view of the bottle thereof, with the dust cap omitted for clarity of illustration.
